UNITED STATES PATENT OFFICE.

STEPHEN JENCICK, OF CHAGRIN FALLS, OHIO.

ENGINE STARTER.

Application filed April 24, 1925. Serial No. 25,587.

This invention relates to improvements in starting devices for internal combustion engines.

The type of device to which the present invention relates comprises a mechanism actuated by a starting motor for moving a starting pinion axially into mesh with the engine gear on the fly wheel so as to transmit the power of the starting motor and thereby turn over the engine, then upon the engine starting under its own power, the comparatively excessive speed thereof will automatically kick the starting pinion out of mesh with the engine gear and return the same to initial, idle position.

The particular object of the present invention is to provide such a mechanism with positive operative connections between the starting pinion and the starting motor, which mechanism is comparatively quick-acting and free from sticking, quiet in its operation and comparatively inexpensive to manufacture.

More specifically, the present invention comprises a collapsible link and lever mechanism and cam means for forcing and guiding the starting pinion into mesh with the engine gear and which is provided with a rubber cushioning means for absorbing the shock which would otherwise be transmitted to the starting motor upon bringing the starting pinion into positive driving connection with the shaft of the starting motor.

The present invention consists also in providing a direct bearing contact of the starting pinion with the shaft of the starting motor, such bearing contact being of substantial extent so as to ensure trueness of movement.

Other objects will appear from the following description and claims when considered together with the accompanying drawings.

Fig. 1 is a side view of my improved mechanism shown partly in section and partly in elevation with the casing broken away, the mechanism in this view being shown in initial or idle position; Fig. 2 is a view similar to Fig. 1 but showing the mechanism in fully extended position for the starting operation of the engine gear; Fig. 3 is a view similar to Figs. 1 and 2 but showing the mechanism in intermediate position; Fig. 4 is a plan view of the mechanism in the position shown in Fig. 3 and with the casing in section and with other parts broken away; Fig. 5 is a cross section taken on line 5—5, Fig. 2; and

Fig. 6 is a cross section taken on line 6—6, Fig. 3.

It is to be understood that the present details of mechanism and design as here illustrated may be varied according to the spirit 60 of the present invention, the particular form here shown being merely for purposes of illustration.

The engine gear 1, carried by the fly wheel of the automobile engine, is enclosed in the 65 casing 2 and is adapted to be started by the pinion 3 which is moved into and out of meshing engagement therewith along a longitudinal or axial path, such interengagement being effected by the mechanism now to 70 be described.

Attached to the same casing 2 by means of the bolts 4 is the casing 5 of the starting motor which drives the motor shaft 6 having suitable bearing 7 in the other end of the casing 2. This shaft 6 extends through the starting pinion 3 which is adapted to be moved axially therealong, and which has a direct bearing engagement therewith through a substantial longitudinal extent.

The means for effecting operative and positive connection between the shaft 6 and the starting pinion 3 are enclosed within the housing 8 and the parts are so constructed and arranged that the housing 8 need be given a rotary motion of less than 90° for moving the pinion into mesh with the gear 1. The shaft 6 is positively connected to the rear end of the housing 8 by means of the bolt 9 extending through the rear projection 10 of the housing 8. Rubber cushioning means 11 in the form of short tubes are provided between the bolt 9 and the inside of the extension, as a means of absorbing shock which would otherwise be transmitted from the starting mechanism to the starting motor. As a means of preventing the rubber from being attacked by the oil, I have provided the felt rings 12 at the four points indicated, that is at the ends of each of the tubular rubbers 11.

The hollow swivel mounting 13 is provided with an annular flange 14 at its rear end which is adapted to seat in a correspondingly formed depression in the rear end head of the casing 8 and to be swivelly secured in such position by means of the annular ring 15 which in turn is secured by means of screws 16. The yoke member 17 is pivotally mounted at diametrically opposite points upon the 110

front end portion of the swivel member 13 and is pivotally connected at its middle point by means of a clevis connection 18 to one end of a link member 19 which extends forwardly and is pivotally connected at its other end to one end of a cross head 20 at the point 21. This crosshead is of substantially the same length as the inner diameter of the housing or casing 8, and the opposite end of this 10 crosshead is adapted to be guided in its movement by engagement with the cam edge of the plate member 22 which is secured on the inner side of the casing or housing 8 by means of screws 23, as clearly shown in Fig. 5. 15 There is provided also a slot 24 near the forward end of the casing 8, the slot in this particular instance being formed by cutting out a recess in the forward end portion of the casing and then closing the immediate forward portion thereof by means of said plate 22 already referred to. In other words, the plate 22 performs a double function of providing the front marginal portion 24 and also serving as a cam guide for one end of the 25 crosshead 20, as above referred to. The slot 24 serves as a bearing means for the peculiarly shaped toe portion 25 on the extreme front end of the lever arm 26 which is an extension from one side of the yoke 17 and 30 which forms together therewith a bell crank lever.

The hollow swivel member 13 is provided with a cut-out portion 13^a to receive and provide a seat for the pivotal connection 18 when the parts are in the initial or idle or collapsed position indicated in Fig. 1.

The operation is briefly stated as follows: With the parts in position as indicated in Fig. 1, upon operation of the starting motor, 40 the shaft 6 will turn the casing or housing 8 and, through the connections already described, the pinion 3 will be extended longitudinally or along its own axis into meshing engagement with the engine gear 1. This 45 operation is effected by engagement of the slot 24 with the toe 25 which, upon rotation of casing 8, will transmit such rotary motion through the bell crank lever above referred to, so as to force the yoke member 17 forwardly, this compound movement being permitted by the swivelling action of the member 13. The forward motion of the yoke member 17 moves the crosshead forwardly and consequently the pinion 3 is moved forwardly or longitudinally along its own axis to meshing engagement with the engine gear, the trueness of such movement and engagement being ensured by the extended bearing for the pinion 3. During such movement of the parts, one end of the crosshead 20 is guided along the cam edge of plate 22 until it strikes the shoulder or abutment 22^a at the forward end portion of such cam edge, as illustrated in Fig. 5, whereupon there is 60 produced a direct driving connection be-

tween the shaft 6 and the starting pinion 3. In other words, at this point the casing 8, which is rotated by the shaft 6, is positively locked to the crosshead and hence to the starting pinion. As above explained, any shock 70 which might result from the sudden engagement of the crosshead with the front edge portion of the cam plate 22 will be absorbed by the rubber cushions and hence prevented from being transmitted to the starting motor. 75

It is observed that in order to accomplish this positive driving connection between the shaft 6 and the pinion 3, it is only necessary to rotate the casing 8 through an angle of less than 90°. Furthermore, in following 80 the link and lever mechanism through the operation just now described, it will be observed that in the initial or idle position shown in Fig. 1, the toe 25 occupies a position approximately at the rear end of the 85 opening or slot 24; that in intermediate position, shown in Fig. 3, the toe 25 occupies position substantially in the forward end of the slot 25; and that at fully extended position, as shown in Fig. 2, the toe 25 occupies 90 position again at the rear end of the slot 24 but turned at somewhat less than 90° to its position in Fig. 1.

As soon as the starting motor has, through the positive driving connection above referred to, succeeded in turning the engine gear 1 so as to enable the engine to then start under its own power, the comparatively excessive speed of the engine gear 1 will cause the starting pinion 3 to rotate at increased speed 100 and to run in advance of shaft 6 and hence to turn thereabout, with the result that the connecting mechanism is caused to collapse, whereupon the pinion 3 returns along its axial path to the position indicated in Fig. 1. In 105 other words, the increased speed of the pinion 3 sets up a differential or relative movement between the pinion 3 and the shaft 6, which differential is effective in collapsing or returning the lever and link connections to 110 their initial or idle position.

Thus it will be seen that I have produced a starting mechanism, which is highly efficient because of the extended bearing for the starting pinion, and the positive connections between the pinion and the shaft of the starting motor. This device is also exceedingly dependable because of its comparatively simple structure which is not apt to be hindered in its operation by dirt or other foreign elements. My improved mechanism is at the same time substantially proof against sticking, is decidedly quiet in its operation and is free from the danger of shock being transmitted to the starting motor. Furthermore, I have produced a mechanism which is decidedly compact and in which a comparatively small degree of operative movement is required in the full performance of its functions. Finally, I have 115 120 125 130

produced a device which can be manufactured at a comparatively low cost.

What I claim is:

1. An engine starter device, comprising a starting pinion adapted to be moved axially into mesh with the gear of an engine to be started, a starting motor having a rotary shaft, a rotatable member mounted upon said shaft, means having swivel connection with one end of said member and having operative connection with said pinion for effecting axial movement thereof, and means whereby rotary movement of said member causes actuation of said means. 70
2. An engine starter device, comprising a starting pinion adapted to be moved axially into mesh with the gear of an engine to be started, a starting motor having a rotary shaft, a rotatable casing mounted upon and surrounding said shaft, means arranged within said casing and having swivel connection with one end thereof to permit relative rotation therebetween, said swiveled means also having operative connection with said pinion for effecting axial movement thereof, and means whereby rotary movement of said casing causes actuation of said swiveled means. 80
3. An engine starter device, comprising a starting pinion adapted to be moved axially into mesh with the gear of an engine to be started, a starting motor having a rotary shaft, a rotatable member mounted upon said shaft, means surrounding said shaft and having swivel connection with one end of said member, a lever mechanism mounted upon said swiveled means and having operative connection with said pinion for effecting axial movement thereof, and means whereby rotary movement of said member causes actuation of said lever mechanism. 85
4. An engine starter device, comprising a starting pinion adapted to be moved axially into mesh with the gear of an engine to be started, a starting motor having a rotary shaft, a rotatable casing mounted upon and surrounding said shaft, lever mechanism arranged within said casing and having operative connection with said pinion for effecting axial movement thereof, and means whereby rotary movement of said casing causes actuation of said lever mechanism. 95
5. An engine starter device, comprising a starting pinion adapted to be moved axially into mesh with the gear of an engine to be started, a starting motor having a rotary shaft, a rotatable casing mounted upon and surrounding said shaft, bodily movable lever mechanism arranged within said casing and having operative connection with said pinion for effecting axial movement thereof, and means whereby rotary movement of said casing causes actuation of said lever mechanism. 100
6. An engine starter device, comprising a starting pinion adapted to be moved axially into mesh with the gear of an engine to be started, a starting motor having a rotary shaft, a casing mounted upon and surrounding said shaft and adapted to rotate therewith, means mounted within said casing and
7. An engine starter device, comprising a starting pinion adapted to be moved axially into mesh with the gear of an engine to be started, a starting motor having a rotary shaft, a rotatable member mounted upon said shaft, means surrounding said shaft and having swivel connection with one end of said member, a bell-crank lever mounted upon said swiveled means and having operative connection with said pinion for moving the same axially, and means whereby rotary movement of said member causes actuation of said lever. 110
8. An engine starter device, comprising a starting pinion adapted to be moved axially into mesh with the gear of an engine to be started, a starting motor having a rotary shaft, a rotatable member mounted upon said shaft, means surrounding said shaft and having swivel connection with one end of said member, yoke means pivotally mounted upon said swiveled means, one arm of said yoke means being continued to form a bell-crank lever, said yoke means having operative connection with said pinion for moving the same axially, and means whereby rotary movement of said member causes actuation of said yoke means including the bell crank lever thereof. 120
9. An engine starter device, comprising a starting pinion adapted to be moved axially into mesh with the gear of an engine to be started, a starting motor having a rotary shaft, a rotatable member mounted upon said shaft, means surrounding said shaft and having swivel connection with one end of said casing, yoke means pivotally mounted upon said swiveled means so as to straddle the same, one arm of said yoke means being continued to form a bell-crank lever and terminating in a radially projecting pin, said yoke means having operative connection with said pinion for moving the same axially, and said member being provided with a slot having operative engagement with said pin, whereby rotary movement of said member causes actuation of said yoke means including the bell crank lever thereof. 130
10. An engine starter device, comprising a starting pinion adapted to be moved axially into mesh with the gear of an engine to be started, a starting motor having a rotary shaft, a casing mounted upon and surrounding said shaft and adapted to rotate therewith, means mounted within said casing and

having operative connection with said pinion for effecting axial movement thereof, means whereby rotary movement of said casing causes actuation of said first-named means, 5 means for effecting positive driving connection between said casing and pinion, and cam means for directing said pinion into such driving connection.

11. An engine starter device, comprising a 10 starting pinion adapted to be moved axially into mesh with the gear of an engine to be started, a starting motor having a rotary shaft, a rotatable casing mounted upon and surrounding said shaft, means mounted within 15 said casing and having operative connection with said pinion for effecting axial movement thereof, means whereby rotary movement of said casing causes actuation of said first named means, means for effecting positive 20 driving connection between said casing and said pinion, and cam means carried by said casing for directing said pinion to such driving connection.

12. An engine starter device, comprising a 25 starting pinion adapted to be moved axially into mesh with the gear of an engine to be started, a starting motor having a rotary shaft upon which said pinion is mounted, bell 30 crank lever mechanism adapted when actuated to move said pinion axially into mesh with the engine gear, and a rotatable casing 35 driven by said starting motor and provided with means for actuating said bell crank lever mechanism to effect movement of said pinion axially into mesh with the engine gear and with additional means for positively 40 effecting rotary movement of said pinion when the same is moved into mesh with the engine gear, one of said means being arranged within said casing.

13. An engine starter device, comprising a starting pinion adapted to be moved axially 45 into mesh with the gear of an engine to be started, a starting motor having a rotary shaft, a casing mounted upon and surrounding 50 said shaft, means mounted within said casing and having operative connection with said pinion for effecting axial movement thereof, means whereby rotary movement of 55 said casing causes actuation of said first-named means, cam means provided upon the inside of said casing for directing the first-named means in its movement, and an abutment at the end of said cam means for effecting positive driving connection between said casing and pinion.

14. An engine starter device, comprising a 60 starting pinion adapted to be moved axially into mesh with the gear of an engine to be started, a starting motor having a rotary shaft, a casing mounted upon and surrounding 65 said shaft, means mounted within said casing and having operative connection with said pinion for effecting axial movement thereof, said means including a radially pro-

jecting arm, means whereby rotary movement of said casing causes actuation of said first-named means and an abutment carried on the inside of said casing for engagement by said radial projection so as to establish positive driving connection between said casing and pinion upon completion of the axial movement of said pinion. 70

15. An engine starter device comprising a starting pinion adapted to be moved axially 75 into mesh with the gear of an engine to be started, a starting motor having a rotary shaft, a casing mounted upon and surrounding said shaft, means having swivel connection with one end of said casing and having operative 80 connection with said pinion for effecting axial movement thereof, means whereby rotary movement of said casing relative to said swivel means causes actuation of said means, and shock absorbing means 85 between said shaft and casing.

16. An engine starter device, comprising a starting pinion adapted to be moved axially into mesh with the gear of an engine to be started, a starting motor having a rotary 90 shaft upon which said pinion is mounted, bell crank lever mechanism adapted when actuated to move said pinion axially into mesh with the engine gear, and a rotatable member 95 driven by said starting motor and provided with means for actuating said bell crank lever mechanism to effect movement of said pinion axially into mesh with the engine gear, and with additional means for positively 100 effecting rotary movement of said pinion when said pinion is moved into mesh with said engine gear.

17. An engine starter device, comprising a starting pinion adapted to be moved axially 105 into mesh with the gear of an engine to be started, a starting motor having a rotary shaft upon which said pinion is mounted, bell crank lever mechanism adapted when actuated to move said pinion axially into mesh with the engine gear, and a rotatable casing 110 driven by said starting motor and provided with means for actuating said bell crank lever mechanism to effect movement of said pinion axially into mesh with the engine gear and with additional means for positively 115 effecting rotary movement of said pinion when the same is moved into mesh with the engine gear, said last named means and said bell crank lever mechanism being arranged within said casing. 120

18. An engine starting device comprising a motor, a motor driven part, a starting pinion part having a starting pinion adapted to be brought into mesh with the gear of the engine to be started, and means operated by 125 said motor driven part for moving said pinion axially into mesh with the engine gear and comprising a lever member operatively connected to the motor driven part and the pinion part, a motor driven member, one of 130

said members having a slot and the other member having a pin engaging in said slot whereby, upon rotation of the motor, relative rotation is produced between it and the 5 pinion causing the pin and slot connection to shift the pinion into engagement with the fly wheel.

19. An engine starting device as in claim

18 wherein the motor driven member is provided with a slot and the lever member is 10 provided with a crank arm carrying a pin engaging in said slot.

In testimony whereof I hereby affix my signature.

STEPHEN JENCICK.
